UNITED STATES PATENT OFFICE.

ALEXANDER CHURCHWARD, OF NEW YORK, N. Y., ASSIGNOR TO WILSON WELDER & METALS COMPANY, INC., A CORPORATION OF NEW YORK.

PRESSURE VARIABLE RESISTANCE.

1,413,390.

Specification of Letters Patent. Patented Apr. 18, 1922.

Application filed June 24, 1919. Serial No. 306,372.

To all whom it may concern:

Be it known that I, ALEXANDER CHURCHWARD, a citizen of the United States, residing at New York city, county of New York, and 5 State of New York, have invented certain new and useful Improvements in Pressure Variable Resistance, of which the following is a specification.

This invention is an improvement in that 10 type of pressure-variable resistance consisting in a pile of resistance plates, such as carbon, arranged to be variably compressed together and to conduct the current from plate to plate through the contacts between them. The object of the invention is to effect 15 better cooling of the resistance pile. The invention is well adapted to employment as the controlling resistance in an electrical arc-welding system.

20 One adaptation of the invention is illustrated in the accompanying drawings, in which:

Figure 1 is an elevation of an arc-welding system including the invention;

25 Figure 2 is an elevation of the resistance pile proper, embodying the invention;

Figure 3 is a sectional elevation of the pile taken on the plane 3, 3 of Figures 2 and 4;

Figure 4 is a plan view of a portion of 30 the pile; and

Figure 5 is a perspective view of one of the carbon plates of the pile.

The carbon plates 6 are vertically grooved on one side to form air channels between the 35 adjacent plates of the pile, and each plate is provided with circular notches 7 in its upper and lower edges. The distance between the upper notches is the same as the distance between the lower notches, and the upper and 40 lower notches are vertically opposite to each other, but one vertical edge 8 of the plate extends beyond its adjacent notches considerably further than the opposite vertical edge 9 extends beyond its adjacent notches.

45 Consequently, notwithstanding the plates are all identical in form and size, if they are stacked together and alternately inverted with their notches in alignment, each set of plates will project laterally on one side of the pile, as at 8 in Figure 4, so as to leave 50 cooling channels between them, as at 9 in Figure 4. This arrangement greatly increases the cooling surface presented at the

sides of the pile, and provides the said channels for circulation of cooling air between 55 the vertical margins of the alternate plates.

The relationship of alternate pile plates thus accomplished, is maintained by mounting the pile on two insulating rods 10 which enter the circular notches and are held in 60 suitable brackets 11 and 12 mounted on a back board 13. The plates are also further secured by insulating side rods 14 and 15, extending between these brackets.

Two extra-thick carbon plates 16 and 17 65 may be included at the ends of the pile, and metal thrust-plates 18 and 19 may bear upon these end plates to transmit the compression to the pile. The rear thrust-plate 18 bears upon an adjustable abutment screw 20 passing 70 through the bracket 11, and the front thrust-plate 19 receives the pressure of the thrust-pin 21 forced inward by the upward moment of the controlling lever 22 pivoted in the bracket 12.

75 In the illustrated instance the controlling lever receives its pile-compressing moment from a tension spring 23 connected to its outer end, and this lever moment is varied and controlled by the opposing pull of a solenoid 24 included in the welding circuit in 80 series with the pile 6, welding electrodes 25 and current source 26, all in accordance with principles now known to the art.

The invention may of course be applied 85 in different specific constructions within the spirit and intended scope of the following claims.

I claim:

1. A variable - resistance pile comprising 90 plates of identic form and material and each having one or more edge notches disposed asymmetrically with respect to one axis of the plate, said plates being stacked in alternately reversed series with their notches 95 aligned so as to project the edges of each alternate series beyond the edges of the other alternate series.

2. A variable - resistance pile comprising 100 plates of identic form and material and each having one or more edge notches disposed asymmetrically with respect to one axis of the plate, said plates being stacked in alternately reversed series with their notches 105 aligned so as to project the edges of each alternate series beyond the edges of the other

- alternate series; and a registering guide entering said aligned notches to maintain said relationship of the plates.
3. A variable - resistance pile comprising 5 plates of identic form and material and each having one or more notches in opposite edges disposed asymmetrically with respect to one axis of the plate and asymmetrically with respect to another axis of the plate, said 10 plates being stacked in alternately reversed series with their notches aligned on one side of the pile so as to project the edges of each alternate series beyond the edges of the other alternate series.
4. A variable - resistance pile comprising 15 plates of identic form and material and each having one or more notches in opposite edges disposed asymmetrically with respect to one axis of the plate and asymmetrically with 20 respect to another axis of the plate, said plates being stacked in alternately reversed series with their notches aligned on one side of the pile so as to project the edges of each alternate series beyond the edges of the other alternate series; and a registering guide entering said aligned notches to maintain said relationship of the plates; and one or more side guides engaging said projecting edges of the plates on one or both sides of the pile.
- 25 30 35 40
- In testimony whereof, I have affixed my signature to this specification.

ALEXANDER CHURCHWARD.
